[57] CLAIM

The ornamental design for a magazine binder, as shown and described.

DESCRIPTION

FIG. 1 is an enlarged perspective view of a magazine binder showing my new design;

FIG. 2 is a top plan view thereof;

FIG. 3 is a side elevational view thereof, the undislosed side being the same;

FIG. 4 is a bottom plan view thereof;

FIG. 5 is an end elevational view thereof, the undislosed end being the same;

FIG. 6 is a top plan view of the grid part of FIG. 1;

FIG. 7 is a side elevational view thereof, the undislosed side being the same;

FIG. 8 is a bottom plan view thereof;

FIG. 9 is an end elevational view thereof, the undislosed end being the same;

FIG. 10 is a top plan view of the base part of FIG. 1;

FIG. 11 is a side elevational view thereof, the undislosed side being the same;

FIG. 12 is a bottom plan view thereof;

FIG. 13 is an end elevational view thereof, the undislosed end being the same.
